UNITED STATES PATENT OFFICE.

ALVA HAYS CAVEN, OF YOUNGWOOD, PENNSYLVANIA.

ELECTRIC SIGNAL SYSTEM.

1,066,380.

Specification of Letters Patent. Patented July 1, 1913.

Application filed November 28, 1911. Serial No. 662,866.

To all whom it may concern:

Be it known that I, ALVA H. CAVEN, a citizen of the United States, residing at Youngwood, in the county of Westmoreland 5 and State of Pennsylvania, have invented a new and useful Electric Signal System, of which the following is a specification.

The present invention relates to improvements in electric signals, the primary object 10 of the present invention being the provision of a signaling device the main portion of which is disposed along the right of way of a trolley system, either of the overhead or underground type, a sub-trolley being 15 connected to the overhead trolley wire, whereby as the car passes such a point which is preferably at the beginning and ending of adjoining blocks, a circuit is established including, the sub-trolley and a portion of 20 the rail to actuate a solenoid or electromagnet disposed at the beginning of the block just left by the car and the beginning of the block about to be entered, whereby the signals visually displayed in the block just 25 left are extinguished, while a signal in the block preceding said signals are set, the signals being preferably a plurality of incandescent lights one disposed at the end and beginning of each block and spaced 30 throughout the said blocks whereby cars in the respective block from opposite sides of the block containing the signals are notified.

A further object of the present invention 35 is the adaptation of the present system to an overhead trolley system, combined with a signal lighting system provided separate from the power system, said signal light system having branches connected to the respective mains which parallel the right 40 of way, said branches being provided with a solenoid or electro-magnetically controlled switch operated by the passage of a car at a certain point, said passage of the car at such point bridging the trolley and ground 45 of the overhead system so as to energize the proper solenoid or electromagnet to extinguish the signal lights in the rear of the passing car and energize those in the front thereof in the block about to be entered.

50 A still further object of the present invention is the simplification of a solenoid or electromagnet mechanism for connecting and disconnecting the signaling circuits containing visual signals such as lamps, the 55 same being composed of two oppositely dis-

posed solenoids having mounted concentrically therein an armature rod carrying a contact disk disposed to be moved in a horizontal reciprocating plane to engage one or branch of a lighting system, or cut out 60 switch to properly energize a signal circuit or branch of a lighting system, or cut out the same; or to alternately throw in a circuit containing a plurality of right of way lamps showing that the block is empty, or a plurality of danger lamps to indicate that the 65 block is occupied.

With the foregoing and other objects in view which will appear as the description 70 proceeds, the invention resides in the combination and arrangement of parts and in the details of construction hereinafter described and claimed, it being understood that changes in the precise embodiment of 75 invention herein disclosed can be made within the scope of what is claimed without departing from the spirit of the invention.

In the drawings—Figure 1 is a diagrammatic view showing an overhead trolley system with one complete block and the ending 80 and beginning of adjacent blocks. Fig. 2 is a similar view illustrating a double lighting or signaling system in operable relation thereto. Fig. 3 is a longitudinal sectional view through the casing showing the 85 solenoids or electromagnetically operated switch in circuit energizing position. Fig. 4 is a similar view with parts in circuit cut-out position. Fig. 5 is a section taken on line 5—5 of Fig. 2. Fig. 6 is a sectional elevation of the trolley pole carried mechanism for opening and closing the actuating circuit when in use with an overhead trolley. Fig. 7 is a view illustrating a modified form 90 of sub-trolley contact device, wherein a rod 95 is used in lieu of a wheel.

Referring to the drawings, the numeral 1 designates in Figs. 1 and 2 the overhead trolley wire having connected thereto and projecting to the side thereof a short sub-trolley 2, which is adapted to be contacted by a small contact wheel 3 carried by the trolley pole T, a conductor 4 being bridged between said small contact wheel 3 and the wheel 6 of the car, a manually controlled 100 switch 5 being interposed in said conductor 4 to permit of the closing of the bridge between the sub-trolley 2 and the rail section 7, which is insulated as shown from the 105 main sections of rail of the railway system 110

and is of sufficient length to permit of both trucks of a car to be upon it at the same time. Connected to and leading from the said rail section 7 is a conductor 8, which is connected at one side of the electromagnet 9, or solenoid 9, a conductor 10 leading from the opposite side thereof and thus being connected by a conductor 11 to the grounded rail section 12 of the railway system. By this means it will be seen that as the small contact wheel 3 engages the sub-trolley 2, the switch 5 being closed to form a continuous conductor between the small contact wheel 3 and the wheel 6 of the car, that when the car wheel 6 passes over the short section of rail 7, that a bridged connection between the main trolley 1 and the ground or rail 12 will be made, thus energizing the electromagnet 9, said electromagnet 9 being properly supported along the right of way of the trolley system. Opposed to the electromagnet or solenoid 9 is another solenoid or electromagnet 13, both of said solenoids being connected to actuate the reciprocatory iron core 14 or armature 14, which has connected thereto the insulated supported metallic ring or disk 15, to which is connected a main conductor wire 16, which as shown in Fig. 1 is connected to the wire 17 parallel to the right of way of the railway system and has connected at predetermined points the signal lamps 18, here shown five in number and disposed at equi-distance between the respective sub-trolleys 2 as shown in Fig. 1. Leading from the last lamp 18 is a conductor 19, which is connected to one of the mains 20 of the current supply for the visual signals 18. Disposed in the path of the contact disk 15 and adapted to be engaged thereby, as viewed in Fig. 1, the solenoid or electromagnet 9 being energized so as to move the contact disk 15 into engagement with the contact plate 21, is a conductor 22 which connects said contact plate 21 to the other main 23 of the lamp supply system, thereby closing the branch containing the light 18, thus energizing the lights throughout the right of way between the respective beginning and ending of the blocks, the said lights being energized and lighted during the passage of the car in the direction of the arrow and until the wheel 6 engages the rail section 7 at the extreme right of the block as viewed in Fig. 1, at which time the small contact wheel 3 will engage the sub-trolley 2 at the extreme right energizing the electromagnet 9 at the extreme right causing a bridged current to traverse the conductor wire 10', the electromagnet 13 at the extreme left, the conductor 25, conductor 8, track section 7, car wheel 6, conductor 4, contact wheel 3, sub-trolley 2, and by reason of the fact as the conductor 11, and conductor 25 are branched into the conductor 10', the said electromagnet 13 is energized to

actuate the armature or core 14 pulling the disk 15 to the right as viewed at the left of Fig. 1, disconnecting the same from the switch 21, thus breaking the circuit containing the lights 18 and extinguishing said lights, and causing the contact 15 to engage the spring catch 24 which retains the contact disk 15 in such position until the electromagnet 9 is energized as before mentioned. At the same time with the energization of the electromagnet 13 at the extreme left as viewed in Fig. 1, the electromagnet 9 as viewed at the extreme right is energized and a circuit ahead of the car, such as the one containing the lamps is energized to indicate that the car is entering the block ahead. This system as viewed in Fig. 1 shows a single series of lights and although the same are disposed throughout the length of the respective blocks, it is evident that a single light may be placed at the end of each block and not throughout the right of way, but it is desired to place the same throughout the right of way not only to insure the employees or motorman the position of the respective car between the blocks, but it also can be used to indicate to the general public that a car is within the block and thus be a warning to them as to its approach. As viewed in Fig. 2, the general arrangement of the electromagnets 9 and 13 at the respective ends of the block and the sub-trolleys and track sections are employed, that instead of using a single series of lights 18 as viewed in Fig. 1, it is desired to use two series of visual signal lights, white lights indicating that the block is not occupied while red lights indicate that the block is occupied. In this structure as the car approaches a block as viewed in the drawings and causes a bridge between the sub-trolley 2 and the track section 7, the electromagnet 9 is energized as in the other case, causing the disk contact 15 to be engaged with the left hand spring or contact plate 21, conductor 16 being thrown into the circuit so that a current passes through the conductor 26 energizing the red lights 27 throughout the length of the block, the conductor being bridged and connected to the main supply conductor 29 which as shown receives its supply from the dynamo or other generating machine 30, the other conductor 31 leading from said dynamo or generator machine being connected by a conductor 38 to the switch or contact plate 21 thus completing the circuit for the red signal lights 27; and indicate that a train has entered the block, proceeding in the direction of the arrow Fig. 2.

As the car approaches and causes a bridge between the sub-trolley 2 and the rail sections 7, the electro-magnet 9 as viewed at the right is energized causing a similar cir-

cuit to the one just described to be made in the block ahead, to energize a plurality of red signal lights to indicate that the block is about to be entered and occupied by the car, and simultaneously with the energization of the electromagnet 9, the electromagnet 13 is energized in a similar manner to the energization of the electromagnet 13 at the left as viewed in Fig. 1. In this particular case a circuit is completed through the contact disk 15, conductor 16', conductor 33 containing the white lights 34, which are now energized to indicate that the block is empty or unoccupied, the conductor 35 connecting said lights 34 to the main 36 which receives its current from the dynamo or electric machine 37, a return conductor 31' being connected to the respective dynamo or electric machines 30 and 37, so that the conductor wire 34' connected to the main 31 and the switch 33, will thus complete the circuit and cause the energization of the said white lights 34.

By this construction and arrangement of signal system, it is evident that the block is lighted throughout its length at all times, a white light indicating that the block is unoccupied, whereas the red lights will indicate that the car is within the block at some point between the ends thereof. Further that by the construction and arrangement of the double opposed solenoids and the respective contact plates thereof, with the bridged connections to the overhead trolley and the track section 7, that the respective solenoids are actuated alternately to throw in the proper series of lamps to designate the relative condition of the block just left and the preceding block about to be entered by the car.

In Figs. 3, 4 and 5 the switch or cut-out mechanism is shown in detail and comprises primarily a box or casing C, which is attached so that the core or armature of the solenoid is disposed upon the level, thereby permitting the retention of the disk 15 in either one of the positions as shown in Fig. 3 or Fig. 4 due to the energization of the desired or proper electromagnet, the said disk 15 being held in such position by means of the spring contact plate to which it is thrown into contact until the succeeding energization of the opposite electromagnet or solenoid, at which time the pull upon the core is sufficient to release the contact 15 from the contact plate then engaged, and pull the same into contact to be engaged by the opposite spring contact. By reason of the short length of the sub-trolley 2, the energization of the respective electromagnet or solenoid 13 is for an instant only, thereby causing the quick throw or movement of the contact disk 15 and preventing danger of burn out in the coils due to too sustained a current being bridged or thrown

through the respective coils. If so desired, however, resistances may be placed between the track sections 7 and 12 to properly reduce the current and the consequent danger of burning out of the respective coils 9 or 13.

As viewed in Fig. 6, the trolley pole 39 carries the usual axle 40, having mounted upon the same the usual trolley wheel 41, the said axle 40 having an extension projecting exteriorly of the fork of the trolley pole and carrying thereon an insulating spool or bushing 42, having mounted upon the exterior face, a similarly shaped conducting bushing or sleeve 43, upon which is journaled the sub-trolley contact wheels 3 before described. Connected to the disk portion of the bushing 43 is the conductor 4 heretofore described. It is desired to properly shield the sub-trolley 2 from the elements and especially the ice which often adheres to the trolley wires of an overhead system, and in order to accomplish this, the supporting arms 44 connected or hung in the usual manner, carry the shields or cover 45 provided with the outwardly extending rims or flanges 46, which provide an open ended casing of a greater length than the length of the sub-trolley 2, and so disposed as to shield the main trolley 1 and the sub-trolley 2 at this point from the elements, thus providing at all times a screened conductor wire or sub-trolley 2 at the point of actuation of the signal lamps.

As shown in Fig. 7, the conductor 4 is connected to the flexible contact arm or rod which is used in lieu of the trolley wheel 3, the same being connected to and insulated from the trolley pole 39 and carrying the forked sub-trolley engaging end 3a. This form is shown more as an alternate to the form shown in Fig. 6 and is one that may be readily applied by simply attaching the contact arm 3' to any trolley pole.

By providing the manual switch 5 intermediate of the conductor 4, the same may be cut-out when the car is running between the respective ends of the blocks, and as the motorman approaches the said ends, the said switch 5 is thrown in and the propulsion controller or motor control switch of the motor car thrown out, thus permitting the car to coast over the track section 7 while the contact wheel 3 engages the sub-trolley 2, thus permitting the system to be actuated in a more efficient manner. It is possible however, that the same may be actuated with the switch 5 closed at all times and without the necessity of the motorman throwing out the propulsion current to coast over the track section 7, but the cutting out of the propulsion current is preferable. When the car approaches an insulated track section, the motorman cuts out his propulsion circuit, and throws in the switch 5. In order 130

to prevent the circuit passing through the wire 4 to detrimentally affect the propulsion circuit, the wire 4 is made of a higher resistance than the motor circuit, but as the 5 motorman usually brings his car to a halt, when approaching a signal and reaches out of the car to operate a signal switch, there is no objection to him cutting out the motor circuit. The switch 5 is thrown in, and as 10 the actuation of the solenoids 9 and 13 is automatic the system does not necessitate the moving of the motorman from his post.

What is claimed is:

1. In an electric signal system for electric railways, an over-head trolley, the traffic rails being the return for the traffic current, one of the traffic rails being divided into blocks with a short rail section intervening at the end of each block, an electromagnet at each end of a block, a conductor connecting one electromagnet to the short rail section at one end of the block, a second conductor connecting the two electromagnets, a third conductor connecting the 25 second electromagnet to the main rail, a normally open signal circuit paralleling the traffic rails and including signals and a source of electrical energy, a switch controlled by the electromagnet adjacent the short rail section for closing the signal circuit in the block ahead, while the other electromagnet opens the circuit in the block just left, and means carried by a traveling car constituting a bridging means between the sub-trolley and the short rail section to energize the two electromagnets.

the trolley and the short rail section to energize the two electromagnets.

2. In an electric signal system for electric railways, an over-head trolley, a sub-trolley connected thereto, the traffic rails constituting the return for the traffic current, one rail being divided into blocks with a short rail section intervening at the end of the block and below the sub-trolley, an electromagnet at each end of a block, a conductor connecting one electromagnet to the short rail section at one end of the block, a second conductor connecting the two electromagnets, a third conductor connecting the second electromagnet to the main rail, a normally open signal circuit paralleling the traffic 40 rails and including signals and a source of electrical energy, a switch controlled by the electromagnet adjacent the short rail section for closing the signal circuit in the block ahead, while the other electromagnet opens the circuit in the block just left, and means carried by a traveling car constituting a bridging means between the sub-trolley and the short rail section to energize the two electromagnets.

In testimony that I claim the foregoing as my own, I have hereto affixed my signature in the presence of two witnesses.

ALVA HAYS CAVEN.
